UNITED STATES PATENT OFFICE.

GEORGE J. CARTER, OF BROMBOROUGH, ENGLAND.

INTERNAL-COMBUSTION ENGINE.

1,305,193.

Specification of Letters Patent. Patented May 27, 1919.

Application filed October 30, 1918. Serial No. 260,389.

To all whom it may concern:

Be it known that I, GEORGE JOHN CARTER, a subject of the King of Great Britain, residing in Bromborough, in the county of 5 Chester, England, have invented certain new and useful Improvements in Internal-Combustion Engines, of which the following is a specification.

The invention is illustrated in the accompanying drawings, in which by way of example, two types of fittings or housings are shown each adapted to carry the starting air admission valve, the safety valve and the indicator cock connection each fitting being 10 15 20 provided with a single stem with the bore of which these valves and connection communicate; the drawings also show the preferred mode of making joint between the stem and the liner and between the stem and the cylinder wall.

Figure 1 is a side elevation in section on the line I, I, of Fig. 2, and

Fig. 2 is an end elevation in section on the line II, II, of Fig. 1, the parts behind the 25 plane of section being omitted.

Figs. 3 to 6 are views of a modified form of fitting, Fig. 3 being a side elevation in section on the line III, III, of Fig. 4.

Fig. 4 is an end elevation in section on the 30 line IV, IV, of Fig. 3 with the parts beyond the plane of section omitted.

Fig. 5 is a part sectional view on the line V, V, of Fig. 4 which passes through the center line of the studs.

Fig. 6 is a transverse section on the line VI, VI, of Fig. 3 and

Fig. 7 shows the general arrangement, and is a plan in transverse section through a pair of adjacent liners.

Referring in the first instance to Figs. 1 40 and 2,—

A' is the stem of the fitting or housing A, the bore a' of which opens out into a chamber a which communicates with:—a chamber b having a valve seating b' to take the safety valve B; a chamber C (see Fig. 2) having a valve seating c' to take the starting air admission valve C; and with the passage way d opening into the screwed bore d' of the boss D to take the indicator cock fitting.

E is the cylinder liner which is drilled with a stepped socket hole e' to take the nose a' of the stem A' the joint being made be-

tween the stem and the liner by means of 55 the washer e'. The jointing pressure is obtained by means of studs S screwing into non-through holes s' in the liner and passing through the body of the fitting or housing the latter with its stem being drawn up 60 by the nuts s'.

This arrangement of the studs will be understood by reference to Fig. 5 which illustrates a similar arrangement of studs in a modification. The studs S are not directly connected to the cylinder wall F, the latter having an opening f' concentric with the socket hole e' in the liner. Through the opening f' a distance piece or sleeve G passes, which sleeve is bored to fit the exterior of the valve housing stem A'. The studs pass freely through holes in the sleeve and the flange g' of the latter makes joint with a suitable seating e' formed in the exterior of the liner E. The joint between 70 the outer face g' of the sleeve and a suitable facing f' on the exterior of the cylinder wall is made by means of a thin washer H of suitable material adapted to stand high temperature, which washer has a central annular U-shaped portion h' to give it the necessary flexibility to allow for imperfect alinement or unequal expansion. The joint between the flange g' of the sleeve and the liner seating e' and between the 75 washer H and the outer face G' of the sleeve, may be made through intermediate nuts s' on the studs, which nuts bear on the washer plates h'. Interposed between the nuts s' and the plate h' is a spring washer s'. It will be 80 seen that by means of this construction the joint between the stem and the liner which is subjected to the pressure in the cylinder is made tight by direct connecting means and independently of the joint between the stem 85 and the cylinder wall.

The joint between the outer portion of the washer H and the facing f' is made by the washer plate h' held in position by the heads j' of the studs J, (see Fig. 5 which 90 shows these parts in a modification).

The spindle b' of the safety valve B is enlarged and recessed where it passes through the sleeve b' and it carries a piston b' fitting the bore of the spring casing b' and the 105 spring b' is interposed between this piston and the screwed sleeve b'; b' is a connection for an air inlet pipe, for pneumatically lift-

ing the safety valve, and b^x is the connection for the safety valve blowoff.

The spindle c^2 of the starting air valve C is fitted with a packing piston c^3 actuating 5 piston c^4 and spring c^5 ; and the casing closed-in by the screwed cap c^6 fitted with means c^7 for grinding in the valve C; the facing for the starting air supply connection is on the front of the fitting and communicates with the chamber c by means of a suitable 10 port.

The valve C is withdrawn through the opening K fitted with the screwed cap k^1 .

Referring now to Figs. 3 to 6—as before, 15 A is the fitting or housing, A' is the stem e^1 the opening in the liner wall e^2 the jointing washer between the nose of the stem and the cylinder wall, the joint as before, being made by studs S (see Fig. 5) which screw into the 20 non-through holes s^1 in the liner, the fitting A and stem A' being forced axially into position by the nuts s^2 . G is the sleeve the flange g^1 of which makes joint with a suitable seating e^3 formed in the exterior of the 25 liner. The end of the sleeve has a rim g^4 which fits in a corresponding socket in the liner, and joint between the outer face g^2 of the sleeve and the facing f^2 on the exterior of the cylinder wall is made by the 30 washer H as described, the arrangement being clearly shown in Fig. 5 and the joint between H and the sleeve being made by the nuts s^3 on the studs S and the joint between H and the facing F being made by the 35 studs J.

As before, the bore a^1 of the stem opens 40 into the chamber b which is provided with a valve seating b^1 to take the safety valve B, the enlarged portion b^2 of the spindle of which fits the sleeve b^3 ; b^4 is a packing piston fitting the cylindrical bore of the casing 45 b^5 ; b^6 is the connection for an air inlet in the pipe for pneumatically lifting the safety valve, and b^x is the connection for the safety valve blow-off.

In order to keep the overall dimensions of the fitting and valves within the smallest limits so as to permit of its use in a confined space, the safety valve spring b^6 is carried 50 in a spring box b^9 (see Fig. 4) being interposed between the end of the box and the sleeve b^{10} . This sleeve presses on the stud b^{11} of the lever b^{12} pivoted in the fitting at b^{13} , and the pressure is transmitted to the 55 safety valve through a corresponding stud b^{14} at the other end.

As before, the bore a^1 of the stem of the fitting communicates with the chamber C and is provided with a valve seating c^1 to 60 take the starting air admission valve C. Unlike the modification of Figs. 1 and 2, the seating c^1 is formed on a sleeve c^9 held in position in the fitting by the nut c^8 so that the valve C and the packing piston and 65 sleeve c^9 may be removed together.

The actuating piston c^4 is controlled by the spring c^5 interposed between it and the spring sleeve c^6 , and the piston c^4 is connected to the valve C through the rod c^{10} pivoted to the end c^{12} of the lever c^{11} fulcrumed on the radius link c^{13} , the opposite end c^{14} of the lever c^{11} being pivoted to the spindle of the valve C, the port c^{15} (see Fig. 3) terminating in a facing c^{16} , forming the connection for the starting air supply. 75

Referring now to Fig. 7 which shows a pair of cylinders F cast integral with each other, A' is the stem of the multiple valve housing A, and O is the stem of the housing of the fuel valve which may be of the ordinary Diesel type. 80

It will be seen that the two openings e^1 are at opposite ends of the transverse center line l , l , and this gives the symmetrical arrangement described and leaves the portion 85 of the liner on opposite sides of the line l , l , of solid construction to resist the exceptionally severe stresses to which it is subjected. The other portions shown in Fig. 7 are lettered to correspond with the figures already described.

It will also be clear from this figure that the adjacent portions of the water jacket render it impossible to locate the multiple openings, where each valve and connection 95 has its own fitting, symmetrically around the liner.

It is to be understood that while I prefer to make the multiple valve housing A to carry the valves and connection described, 100 and the housing O to carry the fuel valve of the Diesel type, these valves and connections may, in certain cases, be distributed otherwise between the two fittings, though better and more convenient results will be 105 obtained by reserving the housing O for the fuel valve alone.

In some cases, owing to the size of the engine, it becomes necessary to provide two fuel valves, and in this case also it will be 110 seen that by using a multiple valve housing for the valves and connections, a symmetrical arrangement of the openings in the liners can be preserved.

In the ordinary operation of the engine 115 and for testing purposes, the valve B requires to be opened from time to time, and as in a multiple cylinder engine there will be a number of these valves, the provision of inter-connected mechanical gear for operating them adds unnecessary complexity to the engine. The provision of an inlet b^8 as shown in Fig. 1 and the connection of these inlets to a common air pressure pipe forms a cheap, simple and effective method of 120 unseating the valves.

The valve C, Fig. 4, like the valve C Fig. 2 is operated by a spring-controlled piston c^4 . The valve is opened by the admission of pressure air into the space on the side of 130

the operating piston c^4 remote from the spring c^5 , which pressure overcomes the said spring and opens the valve.

I claim—

- 5 1. In combination with the cylinder and its liner of an internal combustion engine, provided with openings in alinement, a valve housing provided with a stem having a faced joint with the liner, a connection between the housing and the cylinder wall including a flexible member and studs by which the housing is held to the liner, substantially as described.
- 10 2. In combination with the cylinder and its liner of an internal combustion engine, provided with openings in alinement, a valve housing provided with a stem having a faced joint with the liner, a sleeve surrounding the stem of the housing and bearing on the liner, a flexible washer bearing on the sleeve and the cylinder wall, studs for holding the housing to the liner, and nuts on the studs for pressing the washer against the sleeve and holding the sleeve against the liner, substantially as described.
- 15 3. In combination with the cylinder of an internal combustion engine, a multiple valve housing, a safety valve and a starting air admission valve mounted therein, said housing having chambers arranged laterally in respect to said valves, springs in the

chambers and external levers between said springs and the valves, substantially as described.

4. In combination, the cylinder and its liner, a valve housing having a stem passing through the cylinder and bearing upon the liner, flexible joint means between the housing and the cylinder and studs for holding the housing to the liner, said studs having means for holding the flexible joint means in place, substantially as described.

5. In combination, a cylinder having a liner, said parts having openings in alinement, a valve housing having a stem passing through the opening in the cylinder and seated about the opening in the liner, a sleeve surrounding the stem and seated against the liner, studs passing through the housing and through the sleeve into the liner, a flexible washer bearing on the outer end of the sleeve and the outer face of the cylinder wall and nuts carried by the studs to press the washer into place, substantially as described.

In witness whereof I have set my hand in presence of two witnesses.

GEO. J. CARTER.
